DESIGN FOR A BABY DISH

David Chapman, Chicago, Ill., and Wayne Ramsay, Madison, Wis., assignors to HanksCraft Company, Madison, Wis., a corporation of Wisconsin

Application January 31, 1947, Serial No. 136,604

Term of patent 14 years

(Cl. D44—15)

To all whom it may concern:

Be it known that we, David Chapman and Wayne Ramsay, citizens of the United States, residing at Chicago, in the county of Cook and State of Illinois, and at Madison, county of Dane and State of Wisconsin, respectively, have invented a new, original, and ornamental Design for Baby Dish, of which the following is a specification, reference being had to the accompanying drawing, forming part thereof.

In the drawing, Figure 1 shows a perspective view of a baby dish, showing our new design; and Fig. 2 shows a top plan view of the baby dish illustrated in Fig. 1.

We claim:

The ornamental design for a baby dish, as shown.

DAVID CHAPMAN.
WAYNE RAMSAY.
